UNITED STATES PATENT OFFICE.

JOSEPH WILLIAM KINCHIN, OF BIRMINGHAM, AND WALTER TRANTER, OF NORTHFIELD, NEAR BIRMINGHAM, ENGLAND.

CARBURETER.

1,280,759.

Specification of Letters Patent.

Patented Oct. 8, 1918.

Application filed August 6, 1917. Serial No. 184,687.

To all whom it may concern:

Be it known that we, JOSEPH WILLIAM KINCHIN, subject of the King of Great Britain, residing at Birmingham, England, and 5 WALTER TRANTER, subject of the King of Great Britain, residing at Northfield, near Birmingham, England, have invented certain new and useful Improvements in or Relating to Carbureters for Internal-Combustion Engines, of which the following is 10 a specification.

The invention comprises improvements in or relating to carbureters for internal combustion engines and refers to carbureters of 15 the type in which two sources of fuel supply are in communication with the carbureter which is provided with control means so that one fuel, the lighter fuel, is mixed with air and the mixture drawn into the engine at 20 starting and during slow running and the other (heavier) fuel is mixed with air and the carbureted mixture is drawn into the engine during normal running.

Gravity valves actuated by the suction of 25 the engine, and piston valves controlled by centrifugal governors are known for making the change from one fuel to another automatic in certain conditions of the running of the engine and for automatically regulating the size of the mixture ports.

The object of our invention is to provide a bi-fuel carbureter in which the control member is operated to determine not only the fuel which is supplied to the engine but 35 also the size of the mixture ports, and the size of the air inlet ports for either fuel.

The invention consists in a hollow moving control member divided into two chambers with separate fuel jets for the different fuels 40 entering the separate chambers of the members, the movement of the member simultaneously controlling both the mixture ports and air inlets as well as determining the fuel which is in use.

45 A convenient embodiment is a hollow control member divided by a diaphragm or wall across the same into two separate compartments, arranged in a hollow body or case into which two fuel connections are made 50 leading from separate sources of supply provided with any known means such as float chambers for preventing flooding. The fuel connections lead to separate jets or spraying devices which enter the hollow control member one in each chamber. In the

body or container two mixture openings are formed, of appropriate size leading to a vaporizer or like means and ultimately to the induction pipe and preferably in the opposite wall we form an air opening or air 60 openings, preferably two to each mixture port. The hollow control member is similarly provided with a mixture port and air inlet or inlets approximately corresponding to those in the body in each of its compartments. The inlets and ports in the member and the body are so arranged relatively to each other that as the hollow control member is moved in the body either one fuel or the other may be brought into communication with the induction pipe and the sizes of the corresponding mixture port and air 65 inlets are regulated as the member moves.

On the drawings—

Figure 1 is an elevation of the improved 75 carbureter.

Fig. 2 is a vertical sectional view on line 2—2 of Fig. 1.

Fig. 3 is a vertical section on line 3—3 of 80 Fig. 2.

Fig. 4 is a view similar to Fig. 2, being a vertical section on the line 2—2 of Fig. 1, but showing the parts in a different position from that shown in Fig. 2.

In this example of construction we employ 85 two supply connections *a* of any suitable kind from float chambers *b* of any approved design to the carbureting chamber *c*. From each supply is a jet tube *d* *e* respectively projecting into the carbureter chamber which 90 may conveniently be cylindrical at this portion with the axis of the cylinder at right angles or approximately so to the axes of the jet tubes. The nozzle *d* in the example is the light fuel nozzle and *e* the heavy fuel 95 nozzle.

From the carbureting chamber a connection may lead to any suitable vaporizing chamber *f* preferably provided with tubes *f'* through which exhaust gases are passed 100 which tubes are in the path of the mixture passing from the carbureter and the heating of the fuel resulting from its contact with these tubes on its passage through a heated chamber assists the vaporization of heavy 105 fuel. From the vaporizer the fuel mixture passes to the induction pipe. This part of the apparatus as well as to the fuel supply and level controlling means *b* is not claimed *per se* and may follow on any known lines 110

which are satisfactory for the purpose, but a suitable vaporizer is we believe an essential part of a satisfactory carbureter for heavy fuel.

5 The throttle of the carbureter is of the piston type working in the body aforesaid, and we divide this hollow piston throttle g into two separate compartments g^1 g^2 by means of a diaphragm or wall g^3 .
 10 Into these piston chambers g^1 and g^2 the aforesaid jet tubes d and e project and the piston wall through which they pass has two slots h which allow for the necessary movement of the throttle piston. In the opposite 15 wall of the piston are mixture ports j k which may be brought into communication with outlets l m from the carbureter chamber to the vaporization chamber f and induction pipe of the engine. The outlets l m 20 in the carbureter chamber are preferably in alinement with the jet tubes. In the lower wall of the said chamber and air inlet or inlets are arranged for each supply jet, preferably two for each jet arranged symmetrically 25 on each side thereof as shown at n and o respectively. The apertures m and o on the heavy fuel side are larger than the apertures l and n on the light fuel side as is desirable in dealing with a less readily vaporized oil. In the piston wall are similar 30 air inlets lettered q and r respectively, but the air inlet and the mixture outlet in each piston chamber are set with relation to the same ports in the carbureter chamber so that 35 when the engine is not running the ports in the heavy fuel chamber g^2 are closed, but those in the light fuel side g^1 are slightly open for starting up.

As the throttle piston is caused to slide 40 by means of its rod s the light fuel ports are first opened while the heavy fuel ports are closed, and when the light fuel ports are full open, the heavy fuel ports are just on the point of commencing to open, and on 45 further movement of the piston the light fuel ports close and the heavy fuel ports open to the desired extent required by the running of the engine. Fig. 2 shows the piston moving to the right with the light fuel chamber ports full open and those of the heavy fuel chamber on the point of commencing to open while Fig. 3 shows the limit of movement in this direction with the light fuel ports closed and the heavy fuel ports 55 full open.

The arrangement of the fuel jets d e in the center of the mixture outlet ports l m in conjunction with the symmetrical disposition of the air inlets q and r with respect 60 to the jets d e is a preferred one as in conjunction with the simultaneous regulation of the mixture ports with the air inlets, it enables practically a constant speed of air over and across the jet to be obtained for 65 varying conditions of throttle opening and

prevents failure of the engine during slow running due to impoverished mixture which is likely to occur when the mixture port is throttled down without corresponding regulation of the air inlet.

70

It will be understood that the size and relation of the various ports on the light fuel side and heavy fuel side will be determined so as to give the best results in practice and our invention is not restricted to 75 any particular arrangement in this respect.

We claim:

1. A carbureter of the type for supplying two kinds of fuel to the engine comprising in combination a carbureter chamber, a movable hollow divided control member therein, means for actuating said member, separate fuel supply means and air inlet means for the separate compartments of the said divided control member and separate mixture 85 outlet ports from said compartments; the movement of said control member simultaneously controlling both mixture ports and air inlets as well as determining which fuel is supplied to the engine.

90

2. A carbureter of the type for supplying two kinds of fuel to the engine comprising in combination a carbureter body having two mixture outlets and two apertures to receive fuel supply means and a plurality of air inlet apertures, a hollow control member which is movable in said body said member being divided into two chambers each having a mixture outlet port, a slot to admit a fuel supply means and air inlet apertures; the ports and inlet apertures of the member and those of the body being arranged so that as the member is actuated to open the ports and apertures of one of the chambers, the ports and apertures of the other chamber are simultaneously closing.

95

3. A carbureter of the type supplying two kinds of fuel to the engine comprising in combination a carbureter body having two mixture outlets and two apertures to receive fuel supply jets, said jets being directed toward said outlets, and said body having a plurality of air inlet apertures disposed symmetrically about said jets, a hollow control member movable in said body and divided 110 by an inner wall into two chambers each chamber having mixture outlet passages and apertures to pass a fuel inlet jet and air inlet passages, said passages and apertures of the control member being arranged for co-operating with those of the body according to the position of the control member.

115

4. A carbureter of the type supplying two kinds of fuel to the engine comprising in combination a carbureter body, a manifold, two apertures to receive fuel inlet means in the wall opposite said manifold and air inlet openings on each side of each of said fuel inlet apertures, a sleeve in said body, said sleeve having two mixture outlets in the part 125 130

toward the manifold, and said sleeve having apertures to receive the two fuel supply means and air inlet openings on each side of said fuel inlet apertures, said apertures and 5 openings in the sleeve communicating with those of the body, a hollow control member in the form of a sliding plunger within said sleeve, means projecting outside said sleeve and said body for actuating said plunger, 10 said plunger being divided into two chambers each chamber having a mixture outlet and air inlet openings and slots to pass the

fuel inlet means which may thus enter each of said chambers, the ports and apertures of said plunger being arranged in relation to those of said sleeve so that when those of one chamber of the member are full open those of the other are closed, and as those of the latter chamber are beginning to open those of the former are beginning to close. 15 20

In testimony whereof we affix our signatures.

JOSEPH WILLIAM KINCHIN.
WALTER TRANTER.
